(57) **CLAIM**

The ornamental design for a utility glove as shown and described.

DESCRIPTION

FIG. 1 is a front perspective view for a utility glove according to my new inventive design;

FIG. 2 is a front elevation view thereof;

FIG. 3 is a left side view thereof;

FIG. 4 is a top view thereof;

FIG. 5 is a right side view thereof;

FIG. 6 is a bottom view thereof; and,

FIG. 7 is a rear view thereof.

The broken lines appearing on the utility glove, represented in FIGS. 1, 2, 3, 4, 5 and 7, represent stitching and form part of the claimed design. The broken lines not appearing on the utility glove in FIG. 1, represent environment of use and form no part of the claimed design.
